UNITED STATES PATENT OFFICE.

GEORGE B. JACKSON, OF CHICAGO, ILLINOIS.

INTERNAL-COMBUSTION ENGINE.

1,191,311.

Specification of Letters Patent. Patented July 18, 1916.

Application filed October 27, 1911. Serial No. 657,039.

To all whom it may concern:

Be it known that I, GEORGE B. JACKSON, a citizen of the United States, and a resident of Chicago, in the county of Cook and State 5 of Illinois, have invented certain new and useful Improvements in Internal-Combustion Engines; and I do hereby declare that the following is a full, clear, and exact description thereof, reference being had to the accompanying drawings, and to the characters of reference marked thereon, which form a part of this specification.

This invention relates to improvements in internal combustion engines of that kind 15 embracing a single cylinder and two pistons operating therein and connected by suitable connecting rods to the cranks of a single crank shaft, and the invention consists in the matters hereinafter set forth and more 20 particularly pointed out in the appended claims.

Among the objects of my invention is to provide a simple and economical internal combustion engine designed to increase the 25 power output of the engine relative to the weight of the engine, fuel consumption, etc., as compared to engines heretofore in use; to provide, in an engine of this character, an arrangement of the inlet and outlet valve 30 mechanisms such as will protect the valves from the destructive action of the explosion within the cylinder; to provide a construction and arrangement of such engines whereby the vaporized fuel may be fired at 35 such a point in the travel of the pistons that the maximum power of the explosive energy is exerted on the crank shaft at approximately the longest lever arm of one of the cranks; to increase the expansion of the fired 40 gases and thereby increase the effect of the explosion to turn the crank shaft, as compared to single piston engines at present in use; to provide a construction of engines wherein a very large part of the force of the 45 explosion in the cylinder is exerted during a relatively small angular movement of the crank shaft, so that the heat units developed by the explosion are to a maximum extent utilized as power to produce rotary motion 50 in the crank shaft, and are to a minimum extent absorbed by the surrounding walls of the cylinder, and to provide an arrangement of the cranks of the crank shaft in an engine having a single cylinder and two 55 pistons therein, so arranged, with respect to the piston travel, and the fuel inlet and

ignition periods that the lever arm of the crank connected with one of the pistons progressively increases as the force of the explosion against said piston progressively 60 decreases, thereby utilizing the force of the explosive energy against said crank to a fuller extent than in internal combustion engines heretofore constructed.

Further objects of the invention will appear from the following detailed description of one embodiment which I have chosen to illustrate my invention. It will be understood however that the details may be greatly varied within the spirit and scope 70 of the invention and that the invention is not limited thereto except as hereinafter made the subject of specific claims.

In the drawings, Figure 1 is a vertical section of an internal combustion engine embodying my improvements. Fig. 2 is a vertical section on the line 2-2 of Fig. 1. Fig. 3 is a partial plan and partial horizontal section of the engine. Fig. 4 is an elevational detail of the inlet and exhaust 80 valve mechanisms. Fig. 5 is a detail illustrating the port opening of the cylinder, taken on the line 5-5 of Fig. 4. Figs. 6 to 13, both inclusive, are diagrammatic views, with the cylinder in section illustrating the 85 successive positions of the cranks and pistons throughout one half of the complete cycle of the operation of the engine.

The engine herein shown is a four cycle engine, having a single cylinder and two 90 opposing pistons. It comprises a cylinder 20 which is open at both ends and is supported at its lower open end on a crank casting 21, and is partially surrounded by a water jacket 22. Within said cylinder are 95 two pistons 23, 24, one operating in each end of the cylinder, and arranged to move away from each other under force of an explosion between them and toward each other under the influence of the momentum of the engine 100 during the scavenging and compression stroke thereof.

25 designates the crank shaft of the engine which is rotatively mounted in bearings 26, 26 in the end walls of the crank casing 21, 105 and said crank shaft 25 is provided at its ends, outside the crank casing, with fly or balance wheels 27, 27. As herein shown, the crank casing is provided with a base 28 by which to fix the engine to a support. The 110 said crank shaft has two side cranks 30 which are arranged in the same radial plane,

and a central crank 29 spaced substantially ninety degrees from the side cranks, the cranks being spaced a fixed angular distance apart.

5 The inner piston 24, or that nearest to the crank shaft, is connected by a connecting rod 32 and a wrist pin 33 to the central crank 29, while the outer piston 23 is connected by means of two connecting rods 35, 35 to the 10 side cranks 30. Said connecting rods are located at the sides of the cylinder and extending upwardly through openings in the crank case and are connected at their upper ends to a cross head 36 which extends 15 through openings in the arms 37, 37, shown as made integral with and extending outwardly from the outer piston 23. The outer end of the cylinder is provided with diametrically opposed clearance notches 38, 38 20 to receive the cross head 36. The cylinder is provided between its end with a bridged port or opening 40 which constitutes both an inlet and an exhaust port. It communicates with a chamber 41 which leads to 25 the exhaust passage 42 and to the inlet passage 43. Any suitable carbureter may be connected to said inlet passage. The latter passage is formed in a casting 44, and the exhaust passage is formed in a casting 30 45, which are connected together by bolts 44'. The passage of the vaporized fuel from the fuel inlet passage to the chamber 41 is shown as controlled by a spring controlled conical disk valve 46 which engages 35 an annular conical seat 47 between the chamber 41 and the passage 43. Said disk valve may be normally held against its seat by means of a spring 48 which surrounds the stem 49 of the valve, outside of the casing 44, and is interposed between said casing and the shoulder 50 at the outer end of said stem. The said valve 46 may be operated 40 to open the same either by positively actuated mechanism driven by suitable cams 45 from the engine shaft, or may be operated by the superior pressure above the same acting against its closing spring.

Arranged between the chamber 41 and the exhaust valve passage 42 is a conical 50 disk valve 51 that is provided with a stem 52 which extends downwardly through said casing and through a vertical sleeve 53 fixed to and extending downwardly from the casing of the exhaust passage. The exhaust 55 valve 51 is held normally against its seat by a spiral expansive spring 55 that is interposed between the casing 45 and a shoulder 56 on the lower end of said stem, said spring being contained within the sleeve 53. The 60 lower, shouldered end of the exhaust valve stem is adapted to bear against a lifter 58, which is vertically guided in a bracket 59 attached to the crank shaft casing. The lifter 58 is adapted for actuation by a cam 60 that is fixed to a shaft 61 mounted in

bearings 62, 62 on the engine frame and provided at one end with a gear wheel 64 that meshes with a pinion 65 fixed to the crank shaft 25, as best shown in Fig. 3. The ratio of the pinion and the gear wheel is such as to drive the shaft 61 and the cam 60 at one half the speed of the crank shaft. 70

The upper or outer piston is provided with a familiar form of spark plug 70 which is connected by a wire 71 with a 75 yielding contact member 72 that is attached to and is insulated from the arms 37 of the outer piston. The said contact member 72 is adapted for engagement with a fixed stud 74 which extends through and is insulated 80 from a bracket 75, that is attached to the outer end of the cylinder, and said stud is adapted for connection, by a wire 76, with one side of a battery embodied in an ignition circuit. The other side of said battery 85 is adapted to be grounded to the engine frame in any suitable manner to complete the ignition circuit.

The operation of a gas engine embodying my invention will be more readily understood from inspection of Figs. 6 to 13, both inclusive, and may be described as follows: In accordance with the present construction, and preferably, the central crank 29, connected with the shorter connecting rod 32 of the piston nearest to the crank shaft, is made longer than the crank 30. Assuming that the cycle of the operation diagrammatically illustrated in Figs. 6 to 13 of the drawings begins with the power stroke of the engine, it will be noted, first, that the pistons 23, 24 most nearly approach each other at or about the positions thereof shown in Fig. 6 and that, therefore, this position indicates approximately the high point of compression of the gaseous fuel charge in the cylinder. Both pistons have been moving in the same direction, during the compression stroke of the engine, but with the piston 24 moving at a speed greater than that of the piston 23, as will be apparent from a comparison of Figs. 13, 6 and 7. With an engine of average speed and with a gaseous mixture of average proportions, if the compressed charge be fired at the point indicated in Fig. 6 the flame velocity will be such, with relation to the positions of the cranks, that the highest pressure of the exploding mixture between the pistons will be attained shortly before the period when the parts reach the positions indicated in Fig. 7, and with the crank therefor off of dead center position. In accordance with the usual gas engine practice, the spark is advanced so as to ignite the compressed explosive mixture a few degrees in advance of the high point of compression pressure, so that the pressure of the exploding mixture is greatest at the time when one of the cranks is approaching a position in which 130

its lever arm is most effective to turn the crank shaft. As the lever arm of the last mentioned crank decreases, the lever arm of the other crank increases, so that thereby the explosive pressure is efficiently impressed on the cranks to produce rotation of the crank shaft throughout the expansion stroke of the engine. The degree of advancement of the spark will, of course, depend upon the speed of the engine, and may depend upon other conditions, such as the quality of the fuel mixture and the temperatures of the fuel mixture and the cylinder walls. An inspection of Figs. 6 and 7 shows that the building up of the explosive pressure between the pistons after the firing of the compressed charge due to the combustion of the fuel mixture is not appreciably opposed by compression pressure. Therefore, the explosive pressure against the pistons is exerted directly, and without appreciable counter-influence, on the crank shaft.

It is one of the characteristic features of my improved engine that the theoretical maximum explosion pressure on the pistons is reached approximately at a time when one of the cranks, to wit, the crank 30, as herein shown, approaches a position to exert its greatest power to rotate the crank shaft, and the relation of the crank travel and high compression to the crank 30 is such that the pressure continues to act with high efficiency upon said crank 30 while it is moving through the arc of its rotary travel in which its most effective lever arm is presented to rotate the crank shaft, or from slightly beyond the position shown in Fig. 6 to about that shown in Fig. 8.

A further important feature of the engine construction lies in the arrangement of the cranks relatively to the positions of the pistons to produce high compression, whereby the fuel mixture may be fired at or about the point of high compression pressure and the maximum explosion pressure may be attained at the time one of the cranks is operating at approximately its longest lever arm to turn the crank shaft.

It is further a characteristic feature of the engine shown that as the lever arm of said crank 30 decreases in passing from the point shown in Fig. 7 to that shown in Fig. 8, the lever arm of the other crank, or the crank 29, progressively increases until it reaches the position shown in Fig. 9. During the entire portion of the cycle just referred to and continuing to the position shown in Fig. 10 the pressure of the explosive charge has been continuously applied to rotate the crank shaft, the highest pressure being exerted against the most effective lever arm of one of the cranks, and the diminishing pressure being exerted against the most effective lever arm of the other crank. Thus, while the effective power applied through the

outer piston 23 to the crank 30 is gradually diminishing by reason of the decreasing lever arm of said crank, the effective action of the inner piston 24 on the crank arm 29 gradually increases, by reason of its increasing lever arm. When the connecting rod 35 reaches a position in line with the crank 30, as shown in Fig. 9, the crank 29 has reached its highest point of efficiency to turn the crank shaft; and, while the energy of the explosion pressure exerted on the pistons has been gradually decreasing, due to the expansion of the ignited mixture, the lever arm 29 has been gradually reaching its greatest efficiency, or the position shown in Fig. 9, so as to, in a manner, compound the lower pressure exerted on the pistons, and thereby, to a minimum extent impress on the crank shaft the gradually decreasing force of the explosive pressure to produce rotary motion of the crank shaft. The force of the explosive energy is utilized on the longer crank 29 to turn the crank shaft through a longer distance than if the cranks were of the same length, whereby the length of expansion is increased. The force of the explosive pressure is substantially spent when the parts reach the positions indicated in Fig. 10, and in the further rotation of the crank shaft the pistons begin to move toward each other to expel the spent gases through the exhaust passage, which is opened at the proper point and said exhaust passage remains open until the inner piston covers the port 40. Furthermore, it will be observed that the effective energy of the pressure of the explosion is applied throughout a relatively short angular movement of each crank shaft and with a relatively long expansion. Therefore, the heat units developed by the explosion of the fuel mixture between the pistons are to a maximum extent utilized to produce rotary motion of the crank shaft, and are to a minimum extent absorbed by the surrounding walls of the cylinder and piston. Thus, heat losses are substantially reduced and the power delivered by the engine correspondingly increased, inasmuch as approximately the entire energy of the explosive force is exerted on the pistons while the crank 30 is passing from its position which corresponds to high explosion pressure, to that indicated in Fig. 9, with the exception of the additional expansion due to the effect of the longer crank 29 in its further travel to or near the point shown in Fig. 10. Moreover, with the arrangement shown, wherein the cranks are spaced at substantially ninety degrees apart, the effective power of the explosive energy is impressed on both cranks in the upper half throw of said cranks, or the points between the dead-center position of each crank and ninety degrees therefrom in both directions. For instance the

effective arcs in which the power strokes are impressed on the cranks 29 and 30 are between the points in which the crank 30 is passing from the horizontal position shown in Fig. 7, or a point slightly in advance thereof, to the vertical position shown in Fig. 9, and while the crank 29 is passing from the vertical position shown in Fig. 7 to the horizontal position shown in Fig. 9. By reason of the said relation of the cranks and the angles between the connecting rods and the cranks during the effective throws of the cranks, the expansion between the pistons is lengthened relatively to the crank travel. I am, therefore, enabled to most effectively utilize the advantage of the piston travel of both pistons, with the result that the expansion distance between the pistons is materially increased, as compared to the angular movement of the cranks.

From an inspection of Figs. 6, 7 and 8, it will be noted that the pistons, after the products of combustion have been expelled from the cylinder, move away from each other a substantial distance before the port 40 is uncovered by the lower piston 24 whereby a partial vacuum is induced in the cylinder, when the port is opened, to quickly draw the charge of combustible mixture into the cylinder and to quickly vaporize the charge by reason of the low pressure within the cylinder. It will, furthermore, be observed that the movement of the pistons away from each other in the first part of the charging stroke and until the port 40 is uncovered (Figs. 7, 8 and 9), is quite rapid, so that thereby little time is given for leakage of air into the cylinder between the pistons prior to the uncovering of the port 40 to effect the low pressure therein induced. By reason of the substantially low pressure or partial vacuum which is induced in the cylinder prior to the uncovering of the port 40 in the charging stroke of the engine I am able to employ lower grades of gasoline or inexpensive petroleum products as the liquid fuel, and at the same time produce the proper degree of vaporization of the fuel when admitted to the cylinder.

It will be understood that my improvements are applicable to two cycle engines, and that the construction will be somewhat varied in the application of said improvement.

I claim as my invention:

1. An internal combustion engine comprising a cylinder, two pistons therein movable toward and from each other, a crank shaft, cranks thereon angularly spaced approximately ninety degrees apart and connecting rods for connecting the cranks to said piston, said cranks being so disposed on the shaft relatively to positions of the pistons when closest together that the cranks travel through the arcs of their throw be-

tween the shaft and cylinder during almost the entire period in which the force of the explosive energy is delivered through the pistons to the crank shaft.

2. An internal combustion engine comprising a cylinder, two pistons in the cylinder and movable toward and from each other, a crank shaft provided with cranks spaced approximately ninety degrees apart and connecting rods for connecting said pistons to said cranks, with the cranks disposed on the side of the shaft adjacent to the cylinder during the effective power stroke of the engine, one of the cranks being longer than the other crank to increase the expansion length between pistons.

3. A four-cycle internal combustion engine comprising a cylinder, two pistons therein movable toward and from each other, a crank shaft, cranks thereon, each connected to one of said pistons, said cranks being spaced at an angular distance apart relatively to the positions of the pistons when closest together, so that one of the cranks operates through approximately its longest lever arm to turn the crank shaft at the time of the maximum pressure of the explosive energy on the pistons, and with the lever arm of the other crank increasing throughout and during the shortening of the lever arm of the first mentioned crank, said cylinder being provided with an inlet port across which one of the pistons travels in position to be covered by one of said pistons when the pistons are closest together in the compression stroke of the engine and to be uncovered by said piston during the charging stroke only after said pistons have moved away from each other a distance to create a substantial vacuum in the cylinder between said pistons.

4. An internal combustion engine comprising a single cylinder, two pistons therein movable toward and from each other, a single crank shaft, cranks thereon with means connecting each crank to one piston, said cranks being spaced at an angular distance apart relatively to the positions of the pistons when closest together so that the compressed charge of fuel between the pistons may be ignited at approximately the high point of compression and the maximum explosive pressure delivered to the pistons at the time one of the cranks is operating at approximately its longest lever arm to turn the crank shaft, and with the lever arm of the other crank increasing during and throughout the decrease of the lever arm of the first mentioned crank, and a single port opening into the cylinder and connected to inlet and exhaust passages and located to be covered by one of the pistons when the fuel charge is ignited, and to be uncovered by said piston during the charging stroke only after the pistons have moved away from

each other a distance to create a substantial vacuum in the cylinder between the pistons.

5. An internal combustion engine comprising a cylinder, with means whereby an explosive mixture may be supplied thereto and spent gases exhausted therefrom, two pistons in the cylinder movable toward and from each other, a single crank shaft, cranks thereon, connecting rods for connecting the 10 cranks to said pistons, said cranks being spaced at an angular distance apart, relatively to the positions of the said pistons when closest together, so that one of the cranks is operated through approximately its longest 15 lever arm to turn the crank shaft at the time of the theoretical maximum explosive pressure on the pistons and with the leverage effect of one crank increasing during and throughout the decrease of the lever arm of 20 the other crank, a spark plug carried by one of the pistons, an ignition circuit terminal connected to and movable with said latter piston, and a fixed terminal electrically connected to the movable terminal.
- 25 6. An internal combustion engine comprising a cylinder, with means whereby an explosive mixture may be supplied thereto and spent gases exhausted therefrom, two

pistons in the cylinder movable toward and from each other, a single crank shaft, cranks thereon, connecting rods for connecting the cranks to said pistons, said cranks being spaced at an angular distance apart, relatively to the positions of the said pistons when closest together so that one of the cranks is operated through approximately its longest lever arm to turn the crank shaft at the time of the theoretical maximum explosive pressure on the pistons, with the leverage effect of one crank increasing during and throughout the decrease of the lever arm of the other crank, a spark plug carried by one of the pistons, a fixed ignition circuit terminal carried by and insulated from the cylinder and a terminal strip carried by said last mentioned piston and having wiping engagement with the fixed terminal.

In testimony, that I claim the foregoing as my invention I affix my signature in the presence of two witnesses, this 25th day of October, A. D. 1911.

GEORGE B. JACKSON.
